UNITED STATES PATENT OFFICE.

FREDERICK R. HIRSH, OF NEW YORK, N. Y.

DESIGN FOR A PLATE FOR HARDWARE.

SPECIFICATION forming part of Design No. 24,784, dated October 22, 1895.

Application filed June 26, 1895. Serial No. 554,153. Term of patent 7 years.

To all whom it may concern:

Be it known that I, FREDERICK R. HIRSH, a citizen of the United States, and a resident of the city of New York, in the county and State 5 of New York, have invented and produced a new and original Design for a Plate, of which the following is a specification, reference being had to the accompanying drawing, forming a part thereof.

10 The drawing is a front view of a plate, showing my design.

The leading features of my design consist of a panel, Romanesque leaves located at each end of the panel, and a vermiform band having coils at the ends of and surrounding the 15 panel and the leaves.

Particularly describing my design, it com-

prises a panel adapted to receive any lettering desired, at each end a Romanesque leaf, surrounded on its exterior and at the edges 20 of the plate by a vermiform band which is looped upon itself. This band connects the two ends by running along the sides of the plate.

Having thus described my invention, the 25 following is what I claim as new therein and desire to secure by Design Letters Patent:

The design for a plate, substantially as herein shown and described.

FREDERICK R. HIRSH.
